GEORGE E. CHATILLON, OF NEW YORK, N. Y., AND ROBERT BINGHAM WASSON, OF CRANFORD, NEW JERSEY, ASSIGNEES TO JOHN CHATILLON & SONS, OF NEW YORK, N. Y., A CORPORATION OF NEW YORK

DESIGN FOR A SCALE DIAL

Application filed April 4, 1929. Serial No. 30,763. Term of patent 14 years.

To all whom it may concern:

Be it known that we, GEORGE E. CHATILLON and ROBERT BINGHAM WASSON, citizens of the United States, residing respectively at New York city, in the county of New York and State of New York, and at Cranford, in the county of Union and State of New Jersey, have invented a new, original, and ornamental Design for Scale Dial, of which the following is a specification, reference being had to the accompanying drawing, forming a part thereof,

Figure 1 is an elevation of our improved design, and

Figure 2 is a horizontal cross-sectional view.

We claim:

The ornamental design for a scale dial as shown.

GEORGE E. CHATILLON.
ROBERT BINGHAM WASSON.
